[57] CLAIM

The ornamental design for a chair, substantially as
shown and described.

DESCRIPTION

FIG. 1 is a perspective view looking downwardly from
a position from above, the front, and to one side of the
chair;

FIG. 2 is a side elevational view of the chair;

FIG. 3 is a front elevational view of the chair;

FIG. 4 is a rear elevational view of the chair;

FIG. 5 is a top plan view of the chair;

FIG. 6 is a side elevational view of the chair of FIG. 2
wherein the cushions have been omitted for conve-
nience of illustration;

FIG. 7 is a front elevational view of the chair of FIG. 3
wherein the cushions have been omitted for conve-
nience of illustration;

FIG. 8 is a rear elevational view of the chair of FIG. 4
wherein the cushions have been omitted for conve-
nience of illustration; and

FIG. 9 is a top plan view of the chair of FIG. 5 wherein
the cushions have been omitted for convenience of
illustration.
